**BUCKLE WITH AUTOMATICALLY OPERATING
POSITIVE RELEASE ACTION**
Frank L. Davis, Fort Salonga, N.Y.
Filed May 26, 1967, Ser. No. 644,757
13 Claims. (Cl. 24—78)

ABSTRACT OF THE DISCLOSURE

Separable companion plates, one being T-shaped and the other having a key-hole slot formation, interlocking to form the buckle structure, have leverage parts which with relative angular movement of the plates, cooperate to positively force the plates into disconnected relation.

FIG. 1, in the accompanying drawing illustrating a present preferred embodiment of the invention, is a plan view showing the companion parts of the buckle in separated relation.

FIG. 2 is a similar view showing the buckle parts in connected relation.

FIG. 3 is a sectional view on substantially the plane of line 3—3 of FIG. 2.

FIG. 4 is an edge view showing the parts angled to effect the automatic release of the buckle parts.

FIG. 5 is a sectional view showing the parts in fully released relation.

FIG. 6 is an edge view showing the head member used as the lever for opening the buckle, instead of the other slotted member, as first illustrated in FIGS. 3, 4 and 5.

FIGS. 7 and 8 are front edge views of the two buckle forming plates.

FIGS. 9 and 10 are side views of the two plates.

FIG. 11 is a perspective view of the buckle in closed connected relation.

FIG. 12 is a detail of a possible modification.

Special objects of the invention have been to provide simple means for affecting the release of a buckle subjected to heavy loading or for other reasons difficult to open.

This has been accomplished by providing a lever on one part of the buckle disposed to relatively shift the two parts of the buckle into released relation when one part, used as a handle, is shifted angularly in respect to the other part.

The buckle of the present invention is of the type disclosed in Patents #3,081,506 of Mar. 19, 1963, #3,222,739 of Dec. 14, 1965, and #3,225,401 of Dec. 28, 1965, consisting of two generally flat sheet metal plates engaged in overlapping relation, with one plate 7, having a projecting neck 8, carrying a head 9, to be passed through an extended portion 10, of a web slot 11, in the other, companion plate 12, and bearing against an inclined abutment wall portion 13, having a reduced width slot extension 14 for such neck portion.

These buckles have met all requirements, particularly for such heavy use as on army pistol belts, but at times may resist quick opening, particularly under heavy loading conditions.

The present invention assures and enables quick, easy opening even under adverse conditions occasioned by loading or by presence of foreign matter causing the plates to stick together, or the like.

The leverage means comprises in the illustration a lever arm 15, projecting from the abutment wall 13 of the plate 12, over the top of the head portion 9 of the first plate 7, in position to force the head portion downward and the plate 12 upward upon the relative rocking movement of these plates to the angle indicated in FIG. 4.

2

The lever arm 15 is shown as an integral extension struck out of the abutment wall at the upper end of the neck receiving extension slot 14 therein, long enough to reach and bear down on the head of the other plate when the two parts are relatively angled to approximately the position indicated in FIG. 4.

When this point is reached, the parts will separate freely and with a quick snap action, if under stress.

To facilitate this freeing action, the head plate 7 is shown provided with abutment lugs 16 struck up at the inner edge of the head, at opposite sides of neck 8, and curved at their contacting faces at 17 to act as bearings rolling over the abutment wall as the plates are rocked one over the other.

These lugs thus form contact abutments at opposite sides of the neck and may serve as guides assisting in directing the plates into their interlocked engagement.

To further this guided engagement of the plates, upstanding lugs may be provided on the slotted plate at opposite ends of the head receiving slot to engage opposite sides of the head, as shown at 18.

When the two plates are to be used for connecting the ends of two lengths of webbing, such as indicated at 19, 20, they may be provided with web receiving slots 11, FIG. 1, but if used for connecting other parts they may be provided with other appropriate forms of connecting means.

The head plate is shown as having a slight offset 23 therein to line up the two connected lengths of belt webbing, but it will be appreciated that if so desired, this plate may be in a single flat plane or curved, or otherwise shaped.

The plates may be quickly and easily connected and disconnected, even under load, or if stuck for any cause, may be quickly and positively forced apart.

The slotted plate is shown as provided with an extended leverage handle 24, for rocking that plate to effect the separation.

If desired, the other, head plate 7, may be provided with a leverage handle portion by extending the head into the form of a projecting handle, as indicated at 25.

Thus either one or both plates may be equipped with a handle extension at the exposed free end of the same, making the buckle convenient for either left or right hand operation.

While particularly designed for military pistol belts and pants belting, it will be realized that the buckle structure may be adapted and used for many different purposes, where parts are to be connected in quickly engageable and releasable relation.

The web ends may be secured to the plates by looping through web slots and stitching or the like as first indicated at 11, but if desired, one or both webs may be adjustably secured, as by means such as disclosed in the patents mentioned above or by other, special means, such as wedge clamps to hold the plates in any selected position on the belting without perforating, stitching or otherwise altering the structure or appearance of the belting.

These clamps, indicated generally at 26, may be built onto either one or both plates by extending bearing lugs 27 down at opposite ends of the plates and pivotally mounting levers 28, therein having angled toothed jaw extensions 29 to grip the under or inner face of the web or belting material.

This structure enables the buckle plates to be attached in adjusted relation without perforating or defacing the belt material in any way.

When the buckle is closed the line of force is lower than the locking mechanism, thus holding the parts engaged in tight relationship until either leverage arm is lifted to alter this condition and release the parts.

The length and position of the trip arm 15 determines

the angle of release, enabling buckles to be made up to separate at different selected angles, and thus to operate with a relatively quick or slow action.

To facilitate adjustment of the clamp 26, the lever 28 may be provided with an extension or extensions 30, FIG. 12, disposed at opposite sides of the belt in convenient position for engagement by a thumb or finger.

Also as shown in this view, the end of the belt may be turned under and secured in that relation to form a stop 31 for preventing accidental removal or loss of the clamp.

What is claimed is:

1. A self-releasable buckle for belts or like purposes, comprising

two substantially flat sheet metal plates having means for attachment of belt webbing or other connecting medium thereto,

one of said plates having a projecting neck and a laterally extended head on the end of said neck, the other of said plates having an upstanding abutment wall with a slot at the foot of the same of a length to pass said head and above that a communicating slot of less length for receiving said neck and locating the laterally extended head in supported engagement with said abutment wall at the opposite sides of said neck receiving slot and

a lever arm projecting from the abutment wall above said head and neck receiving slots, whereby to extend into position above said head when the two plates are assembled as described and thereby adapted to depress said head into alignment with said head receiving slot when said plates are relatively angled to carry said lever arm downward into engagement with the head.

2. The invention according to claim 1 with upstanding lugs at the inner edge of said projecting head, curved to roll in engagement with the abutment wall when said plates are rocked into angular relation as set forth.

3. The invention according to claim 1 in which said lever arm is an integral portion struck out of said abutment wall at the upper end of the reduced length neck receiving slot therein.

4. The invention according to claim 2 in which said lugs are spaced to pass to opposite sides of the projecting lever arm.

5. The invention according to claim 1 with upstanding guide lugs at opposite ends of the head receiving slot for guiding engagement with opposite sides of the head.

6. The invention according to claim 1 with upstanding lugs struck upward from the inner edge of said head in position for engagement with the abutment wall.

7. The invention according to claim 1 with a handle forming leverage extension on the free end of one of said plates and by which that plate may be angularly rocked about the point of engagement with the other plate to effect the release action described.

8. The invention according to claim 7 with said handle forming extension on said slotted plate.

9. The invention according to claim 1 with handle forming leverage extensions on both said plates.

10. The invention according to claim 7 with said handle forming extension projecting from the free end of said lever arm.

11. The invention according to claim 1 with lugs extended angularly from the ends of one of said plates, spaced apart the approximate width of the belt to which the buckle is to be applied, and

a belt engaging wedge clamp pivoted in said lugs in position to engage the inner or under face of the belt material and provided with a leverage extension by which said clamp may be released from the belt material to permit adjustment of the buckle with respect to the belt material and thereby providing aforesaid means for attachment to belt webbing.

12. The invention according to claim 1, with said lever arm of a length to effect alignment of said head with said head slot when said plates have been angled to a predetermined degree of relative inclination.

13. The invention according to claim 11 with a finger engageable lug on the end of said leverage extension disposed in finger accessible position at the edge of the belt material.
